UNITED STATES PATENT OFFICE.

HORACE BARNES, OF SEATTLE, WASHINGTON.

DESIGN FOR A RADIOMETER-CASE.

57,762.

Specification for Design.

Patented May 3, 1921.

Application filed November 16, 1920. Serial No. 424,559. Term of patent 14 years.

To all whom it may concern:

Be it known that I, HORACE BARNES, a citizen of the United States, residing at Seattle, in the county of King and State of Washington, have invented a new, original, and ornamental Design for Radiometer-Cases, of which the following is a specification, reference being had to the accompanying drawings, forming part thereof.

In said drawings, Figure 1 is a view in

front elevation of radiometer showing my new design. Fig. 2 is a rear elevational view of the same. Fig. 3 is a view in side elevation. Fig. 4 is a vertical cross-sectional view.

I claim:

The ornamental design for a radiometer case, as shown.

HORACE BARNES.
